STORM WINDOW AND SCREEN HANGER

Richard J. Haug, Nashua, N. H.

Application January 3, 1933, Serial No. 649,961

4 Claims. (Cl. 16—149)

This invention relates to hangers for storm windows and screens and the like.

One of the objects of the present invention is the provision of a storm window and the like hanger that permits the window to be applied, without the use of ladders and the like, readily to and removed from the window frame from the inside of the house, and without the necessity for using attaching devices, as screws and the like that must be removed and replaced periodically.

A further object of the invention is the provision of a storm window and attaching means for securing it at its four corners to the window frame in such manner that the window can pivot about any of its attaching means so that the window can be opened at either top or bottom or at either side for ventilation, as may be desired from time to time.

Another object of the invention is the provision of a hanging device for storm windows and the like that is simple in construction, strong, and so arranged that when properly installed it is under spring tension and can not rattle when in service.

The hanger embodying the present invention includes a spring lever carried by the window and which is disposed respectively over and under pins carried by the window frame; and a further object of the invention is the provisions of a pin construction wherein the pins are permanently carried by the window frame and, when the window is off the frame and the pins are not in use, the pins can be moved into the frame so that the heads thereof lie practically flush with the frame and do not project therefrom.

A yet further object of the invention is generally to improve the construction of storm window and the like hangers.

Fig. 1 is a front elevation of a window frame and a storm window secured thereon in accordance with the present invention.

Fig. 2 is a perspective detail of Fig. 1, illustrating the disposition of a hanger for holding the storm window open.

Fig. 3 is a side view of one of the storm window hangers in service position, the view being taken along line 3—3 of Fig. 1.

Fig. 4 is an enlarged perspective view of the spring lever of the hanger.

Fig. 5 is a plan view of one of the lever pins in extended position.

Fig. 6 is a sectional view of the pin in concealed position on line 6—6 of Fig. 5.

Fig. 7 is a view similar to Fig. 5 but illustrating a modified form of pin and socket.

The invention is herein illustrated in connection with a storm window 10 and the window frame 12. An identical hanger is adapted to be applied to each of the four corners of the window to lie within the window frame, outside the usual upper and lower windows of the frame, that is to say, between the usual windows of the frame and the storm window, and close to the inner faces of the stiles 14 thereof when the storm window is against the frame and to be releasably connected to the stiles. The hanger includes a lever 16 that is composed of spring steel or other material whereby it is relatively stiff yet sufficiently springy for the purpose and preferably, although not necessarily, is flat. The lever at one end is provided with an eye 18 that is loosely engaged with an eye 20 that is fixed to the window frame. The lever is provided with a straight shank 22 which extends from the eye 18 to an upwardly reflexed portion 24 relatively close to the eye 18 that on the under face of the lever provides an indentation that constitutes a pin seat in which a lever-holding pin is adapted to be located and retained. The lever is extended from the pin seat preferably at a slight downward angle with respect to the shank 22 and thence is reflexed upwardly to provide at its upper face a second indentation that constitutes a second pin seat 26 adapted to receive and retain a second lever-holding pin. The lever is then downwardly reflexed to provide at its under face another indentation that constitutes a third pin seat 28 which is adjacent the pin seat 26. The lever extends beyond the pin seat 28 to form a handle 30 and has an end portion 32 that is reflexed under and into proximate parallel relation with the body of the lever and has a down-turned end 34 that is spaced from the pin seat 28 and serves to engage and retain yieldingly a pin in said seat. The frame is provided with lever-holding pins 36 and 38 which are adapted to be seated in the pin seats 24 and 26 respectively when the window is against the frame. In use, a lever 16 is secured to each of the four corners of the window frame preferably as illustrated in Fig. 1 so that the levers lie close to the inner faces of the stiles 14. In hanging the window, the window is inserted through the frame from the inside of the house and held manually by the upper levers with the bottom of the frame resting upon the window sill 40. The upper levers are then placed over the upper frame pins 36 with the pins in the seats 24. The

levers are then moved downwardly to pivot about the pins 36 and are sprung sufficiently to locate them under the pins 38 and with said pins seated in the pin seats 26 of the levers. The pins 36 and 38 and their disposition on the window frame, and the shape of the lever, is such that the levers must be flexed toward the window frame in order to dispose the levers under the pins 38. The lower set of levers is then similarly disposed over and under their corresponding pins thereby to draw the bottom of the window firmly up against the outside of the window frame. The levers constantly exert a spring tension on the window thereby holding it constantly with spring pressure against the frame, with the parts of the hanger in spring engagement so that there is no looseness between and rattle of the parts when the window is on the frame. The spring tension can be varied by screwing the eye 20 more or less into the window frame. The pins 36 definitely define the position of the storm window on the frame since the pin seats 24 present definite abutments engaged with the pins and transfer the weight of the window to said pins.

The pins and the levers are permanent parts of the window frame and the window and do not require to be removed therefrom and re-applied therein from year to year so that there is no wear on the window and the frame.

With this construction any side of the window can be moved away from the frame, at will, for ventilating purposes. A lever can be detached from its engagement with the two pins and the frame can be pushed outwardly by the lever to cause an upper pin to be received in the spring seat 28 and engaged between the lever and the retaining end 34 thereby releasably to hold the window away from the frame. By positioning the lower two hangers as described and as shown in Fig. 2, the bottom of the window can be moved away from the frame, the upper spring levers yielding sufficiently for the purpose. By positioning the upper and lower left hand hangers 45 in the manner described, the left hand edge of the window can be moved away from the frame. The right hand and also the upper portion can be similarly moved away from the frame for ventilating purposes. This permits the window 50 to be opened in any direction to take advantage of different winds for ventilating purposes.

The pins 36 and 38 are so constructed that they can be moved into positions flush with the faces of the stiles or into extended position as desired. To this end each of the pins is slidably and rotatably received in a tubular socket 42 that is driven into the stile. The pin is provided with a laterally outstanding projection 44 that is movable longitudinally in a longitudinal slot 46 of the socket 42 and in the lateral front extension 48 of said slot. When the projection 48 is in the lateral extension, the pin is held in extended position against axial movement in either direction. When, however, the pin is rotated slightly to position the projection 44 in the slot 46, the pin can be moved axially in a position wherein the end of it is substantially flush with the face of the stile. The pin has an enlarged head 50 which overlies the inner face of the stile and the socket and is maintained slightly spaced therefrom by the shoulder 52 so that a fingernail can be inserted between the head and the stile as illustrated in Fig. 6 to move the pin into extended position.

75 While both the upper and lower pins can be

identical it is preferred to have the upper pin so arranged that it projects further from the window stile than the lower pin at the time the lever is positioned on the pins. When the upper pin projects the same amount as the lower pin, which is only the amount required for the lever to seat freely on the pin under the head thereof, it is found that the lever has to bear first on the head of the upper pin and then to be slid off the head onto the pin during the act of flexing the lever and positioning it on the lower pin. Hence it is preferred to have the head of the upper pin positioned far enough away from the stile to permit the lever to be seated initially thereon behind the head. Hence the upper pin can be constructed as illustrated in Fig. 7. In this modification, the longitudinal slot 46a of the pin socket 42a has two lateral extensions 48a and 48b into either one of which the projection of the pin 36a can be positioned, the outer extension 48b holding the head of the pin far enough away from the stile so that the lever can seat directly upon the pin under the head. The pin can be left as thus positioned or subsequently can be moved inwardly into the position determined by the inner slot-extension 48a. If the pin of Fig. 7 is used for both upper and lower pins, as may be desirable for commercial reasons, the lower pin can be initially positioned with its projection in the inner slot-extension 48a, the extension 48a 30 not being used when the pin is a lower pin.

The eye 20 to which the lever 16 is pivoted, can be the usual screw eye but preferably its shank 20a is screw threaded and passes completely through the window sash and has a nut 20b thereon to secure it to the sash. The eye also is so shaped or arranged that it limits the lateral swing of the lever thereon. For this purpose, the eye is provided with an intermediate arcuate section 20c which passes through the eye 18 of the lever and straight radial side members 20d which lie on opposite sides of the lever-eye 18 and constitute abutments which restrain the lever from being displaced laterally on the eye sufficiently to become positioned between the window and the frame at the time the window is initially positioned on the frame. The eye is held from rotating by having its apex forced into the window frame.

I claim:

1. A hanger for storm windows and the like comprising a member adapted to be secured to a window, and a spring lever pivotally connected with said member having longitudinally spaced indented portions providing pin seats on its opposite faces and a third pin seat spaced beyond the other pin seats and a loop beyond said third pin seat having a reflexed pin-engaging end which overlies and is spaced from the entrance of said third pin seat and is arranged to bear resiliently against a pin therein to hold the pin in said pin seat.

2. A hanger for storm windows and the like comprising a member adapted to be secured to the window, a spring lever having a pivotal connection with said member at one end, a handle at the other end and pin seats on the opposite faces thereof between said handle and member, and pins adapted to be carried by the window frame and to be positioned in said pin seats of said lever, sockets in which said pins are slidably longitudinally adapted to be secured in the window frame, and means for holding said pins removably in outstanding positions in said sockets, comprising projections extended laterally 75

from said pins disposed in and movable longitudinally of the slots in said sockets, said slots having lateral extensions at one end in which said projections are located in the outstanding positions of said pins, said pins having heads thereon which overlie the ends of said sockets, and shoulders under said pins which engage the ends of said sockets and space said heads away from the ends of said sockets.

10 3. A storm window hanger including a spring lever having means at one end adapted for pivotal connection with the window, a pair of pin sockets adapted to be carried by the window frame, and pins movable longitudinally in said sockets, said lever adapted to be sprung over one pin and under another pin to engage said pins and to hold said window against the frame with spring pressure, said pins having enlarged heads and said lever adapted to be disposed upon said

20 pins between the heads and said sockets.

4. A storm window hanger including a spring lever having means at one end adapted for pivotal connection with said window, a pair of pin sockets adapted to be carried by the window frame, pins movable longitudinally in said sockets, said lever adapted to be sprung over one pin and under another pin to engage said pins and to hold said window against the frame with spring pressure, said sockets having longitudinal grooves therein with lateral extensions at one 10 end, said pins having lateral projections which are movable along said slots and the lateral extensions and when in said extensions are held in outstanding position, said pins having heads and shoulders under said heads which engage the 15 ends of said sockets and hold said heads away from the ends of said sockets whereby to permit said heads to be engaged and the pins moved into outstanding position.
